US00D979865S

(12) **United States Design Patent** (10) **Patent No.:** **US D979,865 S**
Brunner et al. (45) **Date of Patent:** **** Feb. 28, 2023**

(54) **BRUSH ROLL**(71) Applicant: **SharkNinja Operating, LLC**,
Needham, MA (US)(72) Inventors: **Charles S. Brunner**, Stockton, NJ
(US); **Xavier F. Cullere**, Newton, MA
(US); **Maxwell Wood-Lee**, Brooklyn,
NY (US); **Daniel R. Der Marderosian**,
Westwood, MA (US); **Adam Udy**,
Sutton (GB); **Steven Gacin**, Needham,
MA (US)(73) Assignee: **SHARKNINJA OPERATING LLC**,
Needham, MA (US)(**) Term: **15 Years**(21) Appl. No.: **29/695,072**(22) Filed: **Jun. 14, 2019**(51) LOC (14) Cl. **15-05**(52) U.S. Cl. **D32/31**
USPC .....(58) **Field of Classification Search**USPC D4/122, 127, 128, 131, 132, 133, 136;

OTHER PUBLICATIONS

U.S. Appl. No. 29/695,078, filed at the United States Patent and
Trademark Office dated Jun. 14, 2019, 41 pages.

Primary Examiner — Kevin K Rudzinski

Assistant Examiner — Richard E Yenchesky

(74) Attorney, Agent, or Firm — Grossman, Tucker,
Perreault & Pfleger, PLLC(57) **CLAIM**The ornamental design of a brush roll, as shown and
described.**DESCRIPTION**FIG. 1 is a front view of a brush roll, showing the new
design;

FIG. 2 is a rear view thereof;

FIG. 3 is a right view thereof;

FIG. 4 is a left view thereof;

FIG. 5 is a top view thereof;

FIG. 6 is a bottom view thereof;

FIG. 7 is a front, top right perspective view thereof;

FIG. 8 is a front, bottom right perspective view thereof;

FIG. 9 is a right, top front perspective view thereof;

FIG. 10 is a right, bottom front perspective view thereof;

FIG. 11 is a front, top left perspective view thereof;

FIG. 12 is a front, bottom left perspective view thereof;

FIG. 13 is a left, top front perspective view thereof; and,

FIG. 14 is a left, bottom front perspective view thereof.
